LOOM STOP DEVICE

Robert Blaise Delaney, Darien, Conn., assignor to Bates Manufacturing Company, a corporation of Maine

Application July 17, 1953, Serial No. 368,743

15 Claims. (Cl. 139—228)

This invention relates to improvements in the automatic filling change and stop motions of a filling change type loom and, more particularly, it relates to improvements in a device for reducing the number of loom stops caused by filling breakage occurring when a new bobbin is introduced into the shuttle, as described in U. S. Patent No. 2,759,497 of Peter Pelletier, granted August 21, 1956.

The filling change type loom, commonly called a Draper or Northrup loom, may be operated in conjunction with several mechanical attachments commonly known as the filling fork motion and the filling feeler motion, the purpose of which is to automatically replenish the filling in the shuttle without interruptions of continuous operation of the loom. It has been found, however, that these automatic motions cannot be used when weaving fine or sheer fabrics because they cause imperfections, such as cracks or thin spots to appear in the woven cloth.

The prior above-identified Pelletier application discloses a loom stop device which in conjunction with the filling fork and feeler motions initiates additional bobbin transfer attempts only when a filling break occurs on successive picks following an original bobbin transfer initiated by the feeler motion. However, if a filling break occurs at any other point of time during the weaving operation, the loom is stopped.

The advantage of such an arrangement can be better appreciated if it is understood that filling breakage occurring four or more picks after a successful bobbin transfer has been effected is a relatively infrequent source of loom stoppage, and that filling breaks at the doff (when a new bobbin is inserted in the shuttle) are one of the commonest sources of loom stoppage. In addition, it has been found that a filling change initiated immediately following a filling break at the doff is less likely to cause an imperfection in the weave. Thus this new loom stop device is designed to initiate a bobbin change only at instances where filling breaks are most frequent and when imperfections in the weave are less likely to occur.

This improved loom stop device accomplishes substantially the same purpose or function as the original Pelletier device but it requires fewer mechanical parts and its installation necessitates only a slight modification of the loom mechanism. In addition, in some of the modifications, this new device has the added advantage of being conveniently interchangeable with certain of the conventional parts of the filling fork motion.

For a better understanding of the present invention, reference may be had to the accompanying drawings in which:

Figure 1 is a plan view of a typical loom stop device embodying the present invention shown in working arrangement with the conventional feeler and filling fork motions;

Figure 2 is a view in section taken along lines 2—2 of Figure 1;

Figure 3 is a view in section taken along lines 2—2 of Figure 1, with the various mechanical parts shown in a different position;

Figure 4 is a schematic side view of another form of this invention;

2

Figure 5 is a schematic side view of still another form of this invention;

Figure 6 is a schematic plan view of still another form of this invention; and

Figure 7 is a schematic side elevation, partly broken away, of the form of the invention disclosed in Figure 6.

The present invention is shown in operative arrangement with a conventional filling fork motion A and filling feeler motion B, with only so much of the loom mechanisms being shown as is necessary to describe this new loom stop device.

Referring to Figures 1 and 2, the conventional filling fork motion A has a filling fork 10, with a hook 11 at one end, which operates in conjunction with a conventional grid mounted on the lay of the loom. The filling fork 10 is pivotally mounted on the right-hand end of a filling fork slide 12, which in turn is carried by a grooved guide plate 14 secured to the breast beam 15.

A conventional part of the loom, known as a filling cam, imparts an oscillating movement to a filling cam follower lever 21 whereby the cam follower lever 21 and a follower hook 25 pivotally mounted on the upper end thereof are moved towards the front of the loom (to the right) on alternate picks.

The follower hook 25 is supported by and slides on a bridge 26 formed at the right-hand end of the fork slide 12, and engages the filling fork hook 11 when the latter is pivoted counterclockwise. If, for example, a filling is interposed between the fork 10 and the grid, when the lay is moved towards the fork 10 in the conventional manner, the filling fork 10 cannot enter the grid. Therefore, the fork 10 is rotated clockwise and the fork hook 11 pivoted up out of engagement with the follower hook 25. However, if a filling is not interposed between the fork 10 and the grid, the fork is not pivoted and, thus, the follower hook 25 engages the fork hook 11 thereby drawing the fork slide 12 to the left.

With reference to Figures 1 and 2, it will be seen that this new loom device C includes a dog 28 which is pivotally mounted on the side of the fork slide 12 by means of a shaft 29. The shaft 29 is secured at one end to the slide 12 by suitable means such as welding, and its opposite end extends through a slot 30 in the dog 28. The dog 28 is maintained in position on the shaft 29 by means of a washer and cotter pin indicated at 31 (see Figure 1). The dog 28 has a downwardly extending shoulder 35 formed at its forward or right-hand end and a horizontally extending shoulder 36 formed integral with its rearward or left-hand end.

When the dog 28 is pivoted clockwise into the position shown in Figure 2, the forward shoulder 35 is placed in position for engagement with the knock-off follower lever 37, and its rearward shoulder 36 is pivoted out of engagement with a corresponding shoulder 38 formed in the upper end of the transfer starter arm 39. It will be noted that the pivotal point of the dog 28 is arranged so that the dog is maintained in this position by the force of gravity. When the dog 28 is pivoted counterclockwise in the position shown in Figure 3, the rearward shoulder 36 is placed at a level for engagement with the shoulder 38 on the transfer starter arm 39 during the next rearward travel of the fork slide 12, and its forward shoulder 35 is then raised out of position for engagement with the knock-off follower lever 37.

The follower lever 37, which is a conventional loom part, is connected by lever 37a to a knock-off lever 37b in a manner well known to those skilled in the art, so that when lever 37 is moved rearwardly (to the left), the knock-off lever 37b is pivoted clockwise and thereby the loom is stopped. The transfer starter arm 39, which is also well known in the art, causes a new bobbin to be

inserted into the shuttle whenever it is moved rearwardly or to the left.

It will thus be appreciated that when the fork slide 12 is moved rearwardly (to the left) by the engagement of the fork hook 11 with the cam follower hook 25 in the manner previously described, depending upon the position of the dog 28, the loom will be stopped or a bobbin transfer will be initiated.

Also, at the same time the filling fork slide 12 is moved to the left, a shoulder 42 (see Figure 1) on the left-hand end of the fork slide 12 engages a corresponding shoulder 43 formed in the upper end of the let-off arm 44, and the latter is thereby moved to the left. The let-off arm 44 is connected with a conventional loom part known as the let-off mechanism, which is arranged so that whenever the arm 44 is moved rearwardly, the conventional take-up roll, on which the woven fabric is wound, is let back a distance of two picks. This motion is necessary in order to prevent a crack from appearing in the woven fabric where a filling is missed. It will be noted that in Figures 2 and 3, the let-off arm 44 is only partially shown in order to simplify the drawings.

On the return movement of the cam follower lever 21 (and the follower hook 25), the fork slide 12 is returned to its initial position by means of a spring attached at one end to the bottom of the fork slide 12 and its other end to the fork slide plate 14. At the same time, a biased spring 45 connected to the shoulder 43 of the let-off arm 44 and the filling fork slide plate 14 returns the let-off arm 44 to its original position. Also, in the event the transfer starter arm 39 has been moved rearwardly, a spring 46 connected to the breast beam 15 at 47 and with the transfer starter arm 39 returns the transfer starter arm to its initial position.

As previously mentioned, the dog 28 is pivotally mounted so that it is normally rotated by means of gravity into the position shown in Figure 2. When in this position the forward shoulder 35 on the dog 28 engages the knock-off follower lever 37, causing the loom to be stopped, whenever the fork slide 12 is moved rearwardly because a filling is not interposed between the filling fork hook 10 and the grid.

The following is a description of the mechanism which, under certain conditions, will rotate the dog 28 counterclockwise, and thereby operate the transfer starter arm 39 whenever the fork slide 12 is moved to the left.

With reference to Figures 1 and 2, the conventional filling feeler motion B, the object of which is to detect the point of approaching exhaustion of the filling carried on the bobbin in the shuttle and then to initiate a bobbin transfer, is actuated by a filling feeler 50 which is mounted to the breast beam 15. Each time the lay is moved forward (towards the feeler 50 and the fork 10), the filling feeler 50 is inserted through a slot in the side of the shuttle then resting in the adjacent shuttle box, and comes in contact with the yarn wound on the bobbin carried therein. At the same time, a filling cam follower trip 51 secured to the upper end of the filling cam follower lever 21, is moved towards (but does not engage) the right-hand end of a feeler slide 53. The feeler slide 53 is pivotally attached to its left-hand or opposite end to the transfer starter arm 39 by means of a pin 54 and cotter pin 55.

When the filling on the bobbin in the shuttle is nearly exhausted, the feeler 50 is moved towards the feeler slide 53, which in turn moves the rod 58 in the same direction (see Figure 1). The end of the rod 58 is attached to a lug 59 which is pivotally mounted in the front (right) end of the feeler slide 53. Thus, when the rod 58 is moved towards the feeler slide 53, the lug 59 is pivoted into such a position that it will engage the filling cam follower trip 51, when the latter is moved towards the transfer starter arm 39. As a result, the feeler slide 53 is shifted to the left, and in turn, the transfer starter arm 39 is moved to the left thereby initiating a bobbin transfer.

A pin 60, secured by suitable means to the side of the feeler slide 53, is disposed just in front of a lever 62, which is part of the new loom stop mechanism C. When the lever 62 is shifted rearwardly (to the left) by the pin 60, the dog 28 is simultaneously pivoted counterclockwise by a mechanical arrangement next to be described.

The lower end 63 of the lever 62 is welded or otherwise secured to the side of a ratchet 65 having two teeth 66 and 67. The ratchet 65 is rotatably mounted on a shaft 69, which is supported in a generally horizontal position just above the fork slide 12 by means of a bracket 70. The bracket 70 in turn is secured to the side of the fork guide plate 14 (see Figure 1) by suitable means.

A rod 74 is pivotally mounted on the upper end of the lever 62, and its opposite end extends through an opening 75 in a second lever 76. The second lever 76 in turn is welded or otherwise secured at its opposite end to the rearward portion 77 of the dog 28. Nuts 78 and 79 wound on the threaded portion 80 of the rod 74 are disposed on either side of the opening 75 in the second lever 76.

Thus, when the feeler slide 53 is moved rearwardly towards the transfer starter arm 39, the lever 62 is rotated counterclockwise by the feeler slide pin 60. This in turn causes the nuts 79 on the rod 74 to engage the second lever 76, and the dog 28 is thereby rotated counterclockwise into the position shown in Figure 3. When in this position, the rearward shoulder 36 of the dog 28 is placed in position for engagement with the transfer starter arm 39 and the forward shoulder 35 is raised out of position for engagement with the knock-off follower lever 37. As a result, on the next successive alternate pick, if the filling is not interposed between the fork 10 and the grid, a second bobbin transfer will be initiated.

In order to pivot the dog 28 clockwise back to its initial position (as shown in Figure 2), after the second bobbin transfer has been initiated, the ratchet 65 is rotated by a pawl 84. The pawl 84 is pivotally mounted by means of a pin 85 between shoulder 86 formed thereon and a cotter pin 87. The opposite end of the pin 85 is adjustably mounted through a slot 89 formed in the cam follower extension lever 90 by means of a washer 92 and nut 93. The lower end of the extension member 90 is secured by suitable means, such as welding, to the upper end of the cam follower lever 21.

The pawl 84 is thus made movably responsive to the conventional oscillating movement of the cam follower lever 21 which, as previously explained, is moved by conventional cam means towards and away from the lay on alternate picks. The teeth 66 and 67 on the ratchet 65 are arranged so that the pawl 84 will rotate the ratchet 65 and the lever 62 clockwise. The nuts 79 on the rod 74 are thereby moved out of engagement with the second lever 76, and thus the dog 28 is rotated counterclockwise into the position shown in Figure 2.

To further explain the operation of the new loom stop device C, it will be assumed that during the normal operation of the loom, the mechanical parts of the new device, as well as those of the filling fork and filling feeler motions A and B, are in the position shown in Figures 1 and 2, respectively. Further, it will be assumed that the filling fork 10 and the filling fork hook 11 are not pivoted clockwise by a filling being interposed between the grid and the fork 10 thus indicating a filling is missed.

As the cam follower hook 25 is moved away from the loom (towards the left) it engages the filling fork hook 11 and causes the filling fork slide 12 to be shifted to the left. As a result, the shoulder 35 on the dog 28, which as previously explained is normally rotated clockwise by gravity into the position shown in Figure 2, engages the knock-off follower lever 37 and the loom is stopped.

Next, referring to Figures 1 and 2 it will be assumed that the fork 10 is pivoted clockwise thus indicating that a filling is interposed between the fork and the grid. It

will also be assumed that when the feeler 50 is brought into contact with the yarn carried by the bobbin in the shuttle, it indicates the yarn is about to be exhausted. As previously described, this causes the feeler slide 53 and the transfer starter arm 39 to be moved rearwardly, thereby initiating a bobbin transfer on the next successive pick. Also, as previously explained, the pin 60 on the feeler slide 53 moves the ratchet lever 62, which in turn causes the dog 28 to be pivoted into position for engagement with the transfer starter arm as shown in Figure 3.

As the cam follower lever 21 is moved towards the lay (to the right) on the return stroke, the pawl 84 engages the first tooth 67 of the ratchet 65 and the latter is thereby rotated clockwise a slight distance but not a sufficient distance to move the dog 28 back into engagement with the knock-off lever 37.

If on the next successive pick, the fork 10 indicates a filling is missed (because the first bobbin transfer was unsuccessful), the fork slide 12 is shifted rearwardly and the rearward shoulder 36 on the dog 28 engages the transfer starter arm 39, thereby causing the latter to be shifted rearwardly. This causes another bobbin to be inserted into the shuttle on the next successive pick.

As the cam follower lever 21 is shifted to the right, the pawl 84 engages the second tooth 66 of the ratchet 65 and thereby pivots the ratchet 65 back to its initial position. As a result, the dog 28 is pivoted clockwise a sufficient distance so as to place the forward shoulder 35 of the dog 28 in front of the knock-off follower lever 37, and its rearward shoulder 36 out of engagement with the transfer starter arm 39 (see Figure 2).

If on the next successive pick or picks, the filling is not interposed between the fork 10 and the grid, the fork slide 12 is again shifted towards the transfer starter arm 39 and the loom is stopped because the shoulder 35 is now placed in position to engage the knock-off follower lever 37.

Thus, it is apparent that immediately following an initial bobbin transfer initiated by the feeler motion B, the new loom device C will initiate a second bobbin transfer attempt should the first one be unsuccessful, and if the second transfer is also unsuccessful it will then stop the loom. This stop motion is necessary because if both bobbin transfer attempts are unsuccessful, it is apparent that mechanical adjustment of the loom is necessary in order to correct the operational failure. Also, if no stop motion were provided the entire battery of new bobbins would be exhausted unless the defect were detected by the operator.

It is important to note that the probability of a successful bobbin change after a first transfer attempt is made is greatly increased because when a bobbin is inserted into the shuttle it is supported along its entire length by the yarn on the bobbin beneath it. Therefore the second bobbin will not be tilted as would be the case where the preceding bobbin is exhausted. In addition, the yarn on the ejected bobbin cushions the shock of the new bobbin upon the latter's entrance into the shuttle.

Figures 4 to 7 disclose further modifications of this new loom stop mechanism. It will be noted that in these drawings, the transfer starter arm 39, the feeler slide 53 and the cam follower lever 21, which were previously described in detail, are schematically shown, and the other conventional loom parts are entirely omitted in order to simplify the drawings. Also, the dog 28, shown in Figures 4, 5, 6 and 7, is pivotally mounted on the fork slide 10 in the manner described in connection with Figures 1-3, and is normally pivoted clockwise by gravity, thereby placing its forward shoulder 35 in position to engage the knock-off lever 37, and with its rearward shoulder 36 out of engagement with the transfer starter arm 39.

With particular reference to Figure 4, it will be noted that the dog 28 is pivoted counterclockwise by means

of a cam member 98 which is rotatably mounted by suitable means such as pin 99, on a side of the dog, near its forward (right-hand) end. An arm 101, which is fastened at one end to the upper edge of the cam 98, extends upwardly in a generally vertical direction and is disposed just in front of the feeler slide pin 60. The cam member 98 is suitably designed so that when the cam arm 101 is pivoted to the left by the feeler slide pin 60, the cam shoulder 102 engages a slide plate 103 mounted on the upper surface 104 of the knock-off lever 37, and thereby the dog 28 is pivoted counterclockwise. As a result, the forward shoulder 35 of the dog 28 is raised out of engagement with the knock-off lever 37 and its rearward shoulder 36 is placed in position to engage the shoulder 38 in the upper end of the transfer starter arm 39.

The return mechanism 105, to rotate the cam 98 clockwise back to its original position (as shown in Figure 4), includes a spring 106 which is connected at its opposite ends to the dog 28 and the cam 98, respectively. A stop member 107 formed in the side of the dog 28 prevents the cam 98 from rotating too far in the clockwise direction.

When the cam member 98 is rotated counterclockwise (by the feeler slide pin 60) a latch member 110, pivotally mounted at 111 to the side of the dog 28, engages a tooth 112 formed in the side of a cam 98, and thus prevents the cam 98 from being rotated in the opposite direction by the spring 106. A compression spring 115 maintains the latch member 110 in close relationship with the cam tooth 112.

One end 116 of a rod 117 is slidably mounted adjacent to the opposite end 119 of the latch member 110 by a slidably mounted channel member 120, secured by rivets 121 to the side of the dog 28. The rod 117 is also slidably supported by brackets 125 and 126 which may be secured to the breast beam 15 (see Figure 1) or to the feeler slide 53. A button 128, which is formed on the opposite end of the rod 117, is disposed adjacent to and just in front of a cam follower lever 21 (or the follower trip 51, see Figure 1). A spring 130 concentrically disposed about the rod 117 and positioned between the first bracket 125 and a collar 131 formed about the rod 117 normally urges the rod 117 towards the follower lever 21 and away from the latch member 110.

As previously explained, the follower lever 21 is oscillated towards and away from the loom on alternate picks by conventional cam means. Thus, the rod 117 is moved by the follower lever 21, and the latch member 110 is pivoted by the opposite end 116 of the rod 117, out of engagement with the cam tooth 112, on alternate picks of the loom.

When the follower lever 21 is moved in the opposite direction, the spring 130 returns the rod 117 to its original position (as shown in Figure 4) and the spring 115 pivots the latch member 110 into engagement with a second tooth 133 formed on the side of the cam 98. As a result, the cam member 98 is rotated clockwise a slight distance by spring 106. It will be noted that this amount of rotation is not sufficient to move the forward shoulder 35 of the dog 28 into engagement with the knock-off lever 37.

Thus, if the first bobbin transfer initiated by the feeler slide 53 is unsuccessful, and a filling is not interposed between the fork 10 and the grid (see Figures 1-3) on the next successive alternate pick (as the follower lever 21 is moved to the left), a second bobbin transfer will be initiated. At the same time, the rod 117 is again moved to the left and the latch member 110 is pivoted out of engagement with the second cam tooth 133. As a result, the cam member 98 is rotated clockwise as far as the stop member 107 will permit, by the spring 106, and the dog 28 is pivoted clockwise by gravity, so that its forward shoulder 35 is placed in front of the knock-off lever 37 and its rearward shoulder 36 is out of en-

gagement with the transfer starter arm 39. Thus, if the second bobbin transfer is also unsuccessful when the dog 28 is moved rearwardly by the fork slide pin 29, the loom is stopped.

If desired, additional means such as a weight or a spring may be utilized to rotate the dog 28 in a clockwise direction. In this connection it will be noted that the dog 28 is not prevented from rotating in either direction by the rod 117 because the channel member 120 supporting the rod 117 is slidably mounted.

The modification disclosed in Figure 5 is similar to the previously described modification shown in Figure 4, except that the return mechanism generally indicated at 135 is modified.

In the modification shown in Figure 5, a pawl 136, which engages teeth 137 and 138 formed along the upper edge of the cam member 140, is pivotally mounted at 141 to the upper end of a lever 142. The opposite end of the lever 142 in turn is pivotally mounted at 144 to the dog 28, and its middle portion 145 is disposed just in front of the end 116 of the rod 117. The rod 117 is similar in design and operation to that disclosed in Figure 4.

A spring 147, disposed between a stop member 148 and the middle portion 145 of the lever 142, urges the lever towards the end 116 of the rod 117, into engagement with a second stop member 149. The stop member 148, which also serves to prevent the cam member 140 from being rotated too far in a clockwise direction, and the stop member 149 are secured by suitable means to the side of the dog 28. The pawl 136 is disposed so that its shoulder 136a is positioned just forward of the cam teeth 137 and 138 when the dog 28 is in position to engage the knock-off lever 37.

A member 60a of rectangular cross-section is secured to the feeler slide 53 (instead of the feeler slide pin 60 shown in Figure 4). The feeler slide member 60a is disposed adjacent to and just in front of the forward edge 140a of the cam member 140. When the feeler slide 53 is moved rearwardly (to the left) the upper edge 151 of the feeler slide member 60a engages the pawl 136 thereby raising the latter upwardly, out of engagement with the cam teeth 137 and 138. Thereafter, the feeler slide member 60a rotates the cam member 140 counterclockwise. In this connection, it is important to note that the member 60a raises the pawl 136 before the cam member 140 is rotated. As a result, the dog 28 is pivoted counterclockwise and its forward shoulder 35 is raised out of engagement with the knock-off follower lever 37 and its rearward shoulder 36 is placed into position to engage the transfer starter arm 39. Thus, in the event the first bobbin transfer is unsuccessful, the dog 28 is in position to engage the transfer starter arm 39 on the next successive alternate pick.

Also, at the same time, the feeler slide 53 is moved to the left, the follower lever 21 is moved to the left thereby causing the rod 117 to pivot the lever 142 in the same direction. On the next pick, when the feeler slide 53, the follower lever 21, and the rod 117 are moved to the right, the pawl 136 drops down into engagement with the first tooth 137. Thereafter, the spring 147 moves the lever 142 and the pawl 136 to the right, thereby rotating the cam member 140 clockwise, a slight distance. As in the previous modifications, this partial rotation of the cam member 140 is not sufficient to move the forward shoulder 35 of the dog 28 into position for engagement with the knock-off follower lever 37.

After the second bobbin transfer has been initiated, and the lever 142 and the pawl 136 have again been pivoted to the left by the rod 117, the pawl 136 engages the second tooth 138 and thus the cam member 140 is again rotated clockwise. As a result, the dog 28 is rotated clockwise (by gravity) into the position shown in Figure 5, with its forward shoulder 35 placed in position to engage the knock-off follower lever 37 and its rearward shoulder 36 out of engagement with the transfer starter

arm 39. Thus, if the second bobbin transfer is unsuccessful, and the dog 28 is moved to the left, the loom is immediately stopped.

Figures 6 and 7 disclose still another modification of this new loom stop device in which the cam member 155 is returned to its original position (to engage the knock-off lever 37) as shown in Figure 7, by means of a timer mechanism generally indicated at 156, in Figure 6.

The cam member 155 is pivotally mounted on a shaft 158 which extends through openings 159 and 160 in the dog 28 and the timer housing 161, respectively. A concentric spring 165 is disposed within a circular cutaway portion 166 near the center of the cam member 155, and its opposite ends are attached to the shaft 158 and to the cam member 155 respectively (see Figure 7). The spring 165 is arranged so that it normally urges the cam member 155 in a clockwise direction.

With particular reference to Figure 6, it will be seen that a circular gear 170 is also rotatably mounted on the shaft 158. The gear 170 is urged towards the cam member 155, by a spring 171 disposed about the shaft 158 and positioned between the gear 170 and the inner wall of the timer housing 161. A circular series of teeth 174 and 175 are formed about the adjacent sides of the cam member 155 and the gear 170, respectively. It will be noted that the teeth 174 and 175 are facing in the opposite directions so that when the cam member is rotated counterclockwise, the inclined rearward edges 174a and 175a thereof are moved into engagement. The gear 170 is thereby moved away from the cam member (against the tension of the spring 171), and the gear is not rotated counterclockwise. On the other hand, when the cam member 155 is rotated clockwise by the cam spring 165, the leading edges of the teeth 174 and 175 are maintained in engagement by the spring 171, and the gear 170 is thereby rotated in the same direction.

The gear 170 engages a gear 178 of smaller diameter carried by a second shaft 179. The shaft 179 is journaled at its opposite ends through openings 180 and 181 formed in the dog 28 and the housing 161. A weighted wheel 185 is also carried by the second shaft 179 and is disposed between the smaller gear 178 and the dog 28.

With reference to Figures 6 and 7, it will be seen that when the feeler slide 53 is moved rearwardly (to the left) to initiate a first bobbin transfer, the feeler slide pin 60 engages an arm 187 which is secured to the upper edge of the cam member 155. As a result, the cam member 155 is pivoted counterclockwise which in turn causes the dog 28 to be pivoted counterclockwise. Thus, the forward shoulder 35, of the dog 28, is raised out of engagement with the knock-off follower lever 37 and the rearward shoulder 36 is placed in position to engage the transfer starter arm 39. Therefore, as in the previously described modifications, if the first bobbin transfer is unsuccessful, a second bobbin transfer will be initiated on the next consecutive alternate pick.

The timer mechanism 156 is arranged so that the cam member 155 is returned to its original position (with the forward shoulder 35 of the dog 28 engaging the knock-off lever 37) as shown in Figure 7, in the same amount of time that it would take the loom to complete four consecutive picks. Therefore, if the second bobbin transfer is also unsuccessful, when the dog 28 is moved to the left, the loom is stopped.

It will be appreciated that the arrangement and design of the various parts in the timer mechanism 156 are subject to considerable modification, and that other types of timer mechanisms well known in the art may be utilized, if so desired. Also, all modifications of this new loom device may be modified in a manner apparent to one skilled in the art, so as to provide a greater or lesser number of bobbin transfers after a first transfer is initiated by the feeler motion.

While this device is described in connection with a particular model of a Northrup loom, it is to be understood that this invention may be applied to other types of looms by a slight modification of various parts. Also, it is to be understood that this new loom stop device may be adapted for use with multiple harness looms and/or when weaving a multicolored fabric without departing from the basic concept of this invention.

Furthermore, it is to be understood that the various mechanical parts of this new loom stop device are subject to considerable modification as would be apparent to one skilled in the art. Therefore, the form of the invention described above should be considered as illustrative and not as limiting the scope of the following claims.

I claim:

1. In a loom for interposing a filling between selected warp ends and including an actuatable filling change mechanism and an actuatable loom stopping mechanism, a device comprising a filling detecting means movable when a filling is missed, a dog adjustable to either of two positions and movable bodily in response to the movement of said detecting means, said dog actuating said loom stopping mechanism when disposed in one position and actuating said filling change mechanism when in another position, means to detect the approaching exhaustion of the filling and then to actuate said filling change mechanism, and means responsive to said means when the latter actuates said filling change mechanism to move the dog temporarily from said one position to said other position.

2. A device as set forth in claim 1 wherein said dog is disposed in position to actuate said loom stopping means and out of position to engage said filling change mechanism at all times except when it is adjusted into position to engage said filling change mechanism when the approaching exhaustion of the filling is detected by said means for detecting the approaching exhaustion of the filling before the detection of a filling miss by the filling detecting means.

3. A device as set forth in claim 1 including a movable lever actuated by said means to detect the approaching exhaustion of the filling, and wherein said means for moving the dog to said other position includes a mechanical connection between said movable lever and said dog.

4. A device as set forth in claim 1 including a ratchet having a plurality of teeth, said ratchet being rotatable from an initial position to another position in response to the detection of the approaching exhaustion of the filling, and a reciprocating pawl to engage said ratchet and return it in increments to the initial position.

5. A device as set forth in claim 4 including means connecting the ratchet and the dog whereby the dog is adjusted from one position to said other position by the rotation of the ratchet from its initial position to said other position.

6. A device as set forth in claim 1 including an adjustable timer mechanism set by said means for detecting the approaching exhaustion of the filling and means responsive to said timer mechanism to effect the return of said dog to said one position.

7. In a loom for interposing a filling between selected warp ends and including an actuatable filling change mechanism and an actuatable loom stopping mechanism, a device comprising a filling detecting means movable when a filling is missed, a dog responsive to the movement of said detecting means to actuate said filling change mechanism in one position thereof and said loom stopping mechanism in another position thereof, a cam means which when moved in one direction moves said dog into position for actuating said filling change mechanism and when moved in another direction moves said dog into position for actuating said loom stopping mechanism, means to move said cam means in a direction to move the dog into position for actuating the filling

change mechanism, and means to move said cam means into position for actuating the loom stopping mechanism after the dog has been moved into position for actuating the filling change mechanism.

5 8. A device as set forth in claim 7 wherein the movement of said cam means in a direction to move the dog into position for actuating the filling change mechanism includes means to detect the approaching exhaustion of the filling.

10 9. A device as set forth in claim 7 wherein said means to move said cam means in a direction to move the dog into position for actuating the loom stopping mechanism includes an adjustable timer mechanism, and means responsive to said timer mechanism to move said cam means in said other direction a predetermined duration of time after said cam means is moved in said one direction.

15 10. In a device as set forth in claim 7 wherein said means to move said cam means in a direction to move the dog into position for actuating the loom stopping mechanism includes teeth formed on said cam means, a movable pawl to engage said teeth, and means to oscillate said pawl and thereby rotate said cam means in said other direction on a predetermined number of picks after said cam means is moved in said one direction.

20 11. In a loom for interposing a filling between selected warp ends and including an actuatable filling change mechanism, an actuatable loom stopping mechanism and a filling detecting means movable towards said filling change mechanism and said loom stopping mechanism when a filling is missed, a mechanism comprising a dog pivotally mounted on said filling detecting means, a first shoulder formed on said dog engageable with said loom stopping mechanism, a second shoulder formed on said dog engageable with said filling change mechanism, a cam member rotatably mounted on said dog, which when rotated in one direction, pivots said first shoulder of said dog into position for engagement with said stopping mechanism, and when rotated in another direction, pivots said second shoulder of said dog into position for engagement with said filling change mechanism.

25 12. A mechanism as described in claim 11 including means on said cam member actuatable by said filling change mechanism to rotate said cam member in said one direction and actuatable means on said dog to rotate said cam member in said another direction a plurality of picks after said means rotates said cam member.

30 13. A mechanism as described in claim 11 including means on said cam member actuatable by said filling change mechanism to rotate said cam member in said one direction and means on said dog to rotate said cam member in said another direction a plurality of picks after said means rotates said cam member.

35 14. In a loom for interposing a filling between selected warp ends, a device for reducing loom stops comprising filling detecting means to detect a filling miss, means to detect the approaching exhaustion of yarn on the bobbin, means to stop the loom, means to initiate a bobbin change, a movable member actuatable by the filling detecting means which, in normal position, effects the operation of the means to stop the loom and, in shifted position, effects the operation of the means to initiate a bobbin change, and means controlled by the means to detect the approaching exhaustion of yarn on the bobbin to move said member to the shifted position.

40 15. A device as set forth in claim 14 including means to maintain said member in the shifted position for a predetermined number of picks, and means to restore said member to normal position to stop the loom after said predetermined number of picks.
